UNITED STATES PATENT OFFICE.

RANDOLPH MCBEE, OF WASHINGTON, DISTRICT OF COLUMBIA.

PIPE-HANGER.

SPECIFICATION forming part of Letters Patent No. 429,357, dated June 3, 1890.

Application filed February 25, 1890. Serial No. 341,724. (No model.)

To all whom it may concern:

Be it known that I, RANDOLPH MCBEE, a citizen of the United States, residing at Washington, in the District of Columbia, 5 have invented certain new and useful Improvements in Pipe-Hangers; and I do declare the following to be a full, clear, and exact description of the invention, such as will enable others skilled in the art to which it appertains 10 to make and use the same.

My invention relates to an improved device whereby water or other pipes may be hung or suspended from ceilings or may be secured in a vertical or inclined position at a suitable 15 distance from upright walls.

It is the object of my invention to provide a simple and inexpensive device for this purpose which may be readily employed in a variety of situations, which is adapted to 20 carry a single pipe or a plurality of pipes of various sizes, which is adjustable to meet the various circumstances under which it may be used, and which can be readily but firmly attached either to a solid beam or to the bottom 25 of a floor or to the laths behind the plaster.

My invention comprises, essentially, a screw-threaded wall-plate and a correspondingly-threaded nipple-plate constructed and adapted 30 to be combined and employed as hereinafter more particularly set forth.

In order to make my invention more clearly understood, I have shown in the accompanying drawings means for carrying the same 35 into practical effect.

In said drawings, Figure 1 is a vertical sectional view of a pipe-hanger embodying my invention and shown as applied to the support of two pipes and as attached to a solid 40 beam, certain additional attachments, which may or may not be employed, being indicated by dotted lines. Fig. 2 is a perspective view of a nipple and transverse plate, the same constituting a part of, but shown as detached 45 from, the complete construction shown in Fig. 1. Fig. 3 is a vertical sectional view of what may be termed the "nipple" or "hanger" plate detached from the wall-plate and provided with pipe-rests separate from or detachable 50 from the plate. Fig. 4 is a perspective sectional view of a modified form of pipe-hanger.

Fig. 5 is a bottom plan or face view of the wall-plate. Fig. 6 is a bottom plan view of the nipple or hanger plate. Fig. 7 is a sectional view of a modified form of hanger especially adapted for steam-pipes.

Referring to the drawings, A indicates a wall-plate, provided with a screw-threaded aperture a, in which is adapted to fit the correspondingly-threaded nipple b, carrying the transverse plate B. The said nipple is provided with a central conical socket b', having at its upper end a perforation b², through which may be passed a screw C, to secure the whole device to a beam, as indicated in Fig. 65 1. Where a solid support like a beam can be obtained, this central screw is a sufficient means of support for the entire hanger; but where a thin partition or a plastered ceiling forms the support I employ small screws of a sufficient number, as indicated at C', which pass through suitable apertures formed in the base-flange A' of the wall-plate.

The transverse plate B, carried by the nipple, is provided with one or more pipe-rests 75 D, which may be formed with the plate, as indicated in Figs. 1 and 2, or may be separate and attachable thereto, as indicated in Figs. 3 and 4, and in the case of the central pipe-rest, in Fig. 1. When said rests D are 80 separate from the transverse plate B, they are attached thereto after having been passed around the pipes P by suitable means, such as screw-bolts s and nuts s'. In order to enable the same nipple-plate to be employed 85 for various diameters of pipe, it is longitudinally slotted, as shown at b³, thus providing for the attachment of straps of different lengths. Such slots may also be provided in the form of plate shown in Figs. 1 and 2, 90 wherein the rests D are integral with the plate, and the device is thus adapted for the attachment of an intermediate separate rest carrying a third pipe, as shown in dotted lines in Fig. 1.

By extending the plate B, as indicated in Fig. 3 and in dotted lines in Fig. 6, a plurality of pipes may be carried by a series of separate rests D.

It will be seen by considering the relations 100 of the wall-plate, nipple-plate, and central screw C that, the nipple b having been in-

serted in the threaded opening *a*, and the screw *C* having been passed through the perforation *b*² and engaged with the beam or other support, the plate *B* may be rotated in the proper direction to bring it to such distance from the wall or support as to meet the pipe or pipes to be supported. The screw *C* is then screwed down to a firm bearing in the socket *b'*, and the wall and nipple plates will be rigidly secured in position. The pipe or pipes *P* are then laid in the pipe-rests *D*, if the latter are of the form shown in Fig. 2. If the rests *D* are separate from the plate *B*, the former are passed around the pipes and secured to the transverse plate by the screws and bolts *s s'*.

If it is desired to support the pipes in such position that gravity cannot be relied upon to keep them in place in pipe-rests of the open form shown in Fig. 2, I employ a plate *E*, (see Fig. 1,) provided with a central opening *e*, screw-threaded to correspond with the thread upon the nipple *b*, the ends of which plate, when it is screwed down upon the nipple, will engage the sides of the pipes opposite to the rests *D*. Such plate *E* is slotted at *e'* to correspond with the slots in the plate *B* and admit of the attachment of a separate central pipe-rest.

In the construction shown in Fig. 7 a separate pipe-rest is pivotally secured to the plate *B* by a bolt running transversely of the pipe and indicated by the letter *s*². This bolt passes through openings in the vertical ends *D'* of the pipe-rest and through similar openings in depending lugs *B'*, formed upon the plate *B*. The hanger is thus adapted to permit a swinging or longitudinal movement of the rest *D* to accommodate the expansion of steam or other highly-heated pipes.

Having thus described my invention, what I claim as new, and desire to secure by Letters Patent, is--

1. In a pipe-hanger, the combination, with a screw-threaded wall-plate, of a correspondingly-threaded nipple having a socket and perforation for a fastening-screw and a transverse plate having longitudinal slots, and a concave pipe-rest carried by said transverse plate, substantially as set forth. 45-

2. In a pipe-hanger, the combination, with a screw-threaded wall-plate, of a correspondingly-threaded nipple having a socket and perforation for a fastening-screw and formed with a transverse plate having longitudinal 55 slots and adapted to receive a concave strap or pipe-rest, substantially as set forth.

3. In a pipe-hanger, the combination, with a screw-threaded wall-plate, of a correspondingly-threaded nipple having a socket and 60 perforation for a fastening-screw and formed with a transverse plate having longitudinal slots, and a concave pipe rest or rests fitting said plate, substantially as set forth.

4. In a pipe-hanger, the combination, with a wall-plate, of a separate transverse plate, said parts having the one an opening or recess and the other a projection or nipple fitting such recess, a central fastening-screw, and a concave pipe-rest carried by the transverse plate, substantially as set forth. 70

5. In a pipe-hanger, the combination, with a wall-plate, of a separate transverse plate, said parts having the one an opening or recess and the other a projection or nipple fitting such recess, means for securing said plates together, and a concave pipe-rest carried by the transverse plate, substantially as set forth. 75

In testimony whereof I affix my signature in the presence of two witnesses.

RANDOLPH MCBEE.

Witnesses:

E. K. STURTEVANT,
M. P. CALLAN.
